CLAIM

The ornamental design for a record adapter, as shown and described.

DESCRIPTION

FIG. 1 is a front, top, side perspective view of an adapter for a record showing my new design;

FIG. 2 is a front view thereof;

FIG. 3 is a rear view thereof;

FIG. 4 is a side view thereof;

FIG. 5 is a top view thereof;

FIG. 6 is a bottom view thereof; and,

FIG. 7 is another front, top, side perspective view thereof. The broken lines in the drawings illustrate environmental material that form no part of the claimed design.
